UNITED STATES PATENT OFFICE

STEPHEN P. ENRIGHT, OF PHILADELPHIA, PENNSYLVANIA

FLUSH VALVE

Application filed June 7, 1928. Serial No. 283,578.

My invention relates to new and useful improvements in a flush valve and has for its object to provide an exceedingly simple and effective device of this description adapted to utilize an air trapped tank of such dimensions as to be placed within the walls of the ordinary building and which will serve to deliver the proper amount of water under pressure to the bowl and automatically shut off the flow of said water at a predetermined time.

With these and other ends in view, this invention consists in the details of construction and combination of elements hereinafter set forth and then specifically designated by the claims.

In order that those skilled in the art to which this invention appertains may understand how to use and make the same, I will describe its construction in detail, referring by numerals to the accompanying drawings forming a part of this application, in which:

Fig. 1 shows my improved flush valve applied to an ordinary bowl and connected with an air confining tank located within the wall of a building.

Fig. 2 is a plan view of Fig. 1.

Fig. 3 is an enlarged central longitudinal section of the valve in its closed condition; the 30 clapper valve member being left in section.

Fig. 4 is a view similar to Fig. 3, showing the valve mechanism open, said mechanism being in section.

Fig. 5 is a central longitudinal section of 35 the clapper carrying member.

Fig. 6 is a bottom view of the clapper carrying member.

Fig. 7 is an end view of Fig. 6.

Fig. 8 is a side view of Fig. 6.

Fig. 9 is a central longitudinal section of 40 the housing into which the clapper carrying member telescopes.

Fig. 10 is a bottom view of Fig. 9.

Fig. 11 is a side view of Fig. 9.

Fig. 12 is an end view of Fig. 11 looking 45 in the direction of the arrow.

Fig. 13 is a section of the casing at the line 13—13 of Fig. 3.

In carrying out my invention as herein embodied, 50 10 represents a relatively small air

trapped tank which is preferably located within the wall of the ordinary building and is supplied with water at any desired point through the service pipe 11 having the valve 12 therein for regulating the flow of water 55 to this tank.

From the bottom of the tank the pipe 13 is led through the wall and has threaded thereon the union nipple 14 carrying the union nut 15 for screwing upon the threads 60 16 formed on the casing 17 of the valve whereby a water-tight connection may be readily made between the nipple and the casing as will be readily understood.

The body of the casing 17 extends downward at an angle and terminates in the delivery pipe 18 through which water is delivered to the bowl and 19 represents an offset for accommodating the stripping dog 20. This dog is secured upon the spindle 21, the 70 latter being journalled in the side walls of the offset in any well-known manner to prevent leakage while permitting the spindle to be turned upon its axis.

The spindle 21 extends outward at one side of the valve and is curved as clearly shown in Fig. 2 and has thereon a suitable handle 22 in proper position for easy access.

23 represents the clapper adapted to close upon the seat 24 and this clapper is secured 80 in any suitable manner to the carrying member 25, said member having a threaded stud 26 projecting therefrom through the clapper and on which is run the counter weight 27 for determining the time relative to the flow of water at which the clapper will be closed as will be hereinafter explained.

The member 25 is preferably tubular shaped having the inclined face 28 against which the clapper is secured and so that the clapper may close in substantially a vertical position while this member extends outward and downward on the axial lines of the casing and projects into the housing 29, the latter having the slots 30 formed in the outer portion thereof and through these slots passes the guide pin 31 carried by the casing. This pin while permitting the sliding of the housing back and forth within the casing pre- 100

vents the turning thereof upon its axis for the purpose hereinafter explained.

The housing 29 has formed in the inner portion thereof the semi-circular seats 32 and the angular slots 33 in which the lugs 34 are positioned, these lugs having circular hubs fitting in the semi-circular seats and extensions fitting in the angular slots as clearly shown in Fig. 3; the lugs 34 being projected from the sides of the clapper member. This arrangement causes the housing to move back and forth with the clapper member while permitting said member to be tilted independently of the housing and the particular shape of the lugs 34 and the seats and angular slots prevent the disengagement of the clapper member and the housing during the various movements thereof.

Since the housing is held against axial rotation by the pin 31, the lugs 34 in engagement with said housing as just described will also prevent the clapper member from rotation upon its axis and thus always maintain the clapper in proper relative position to its seat.

A rib 35 carried by the housing serves as a riding surface for the clapper member in its to-and-fro movements relative to the housing, thus preventing undue friction.

The clapper member is cut away as indicated at 36 so as to permit the free flow of water to the interior of the member when the clapper is open and also to direct the flow of the water at an upward angle to hold the valve open as will be presently explained.

37 represents a tongue formed with the member 25 and this tongue terminates in a heel 38 against which the dog 20 acts to force this member inward and upward in order that the shoulder 39 carried by the tongue may be brought into engagement with the shoulder 40 formed in the casing.

From the foregoing description, it will be obvious that when the handle 22 is raised, the dog 20 will force the clapper off its seat, tilting the member 25 upon the rib 35 and engaging the shoulder 39 with the shoulder 40 thereby lifting the inner end of this member and the clapper carried thereby so that the flow of water from the tank will pass beneath the clapper through the openings 36 and against the upward wall of the member 25, thus holding the clapper open as long as the force of flow is sufficient to maintain these parts in this position and sustain the counter weight 27 in its elevated position; but when the force of the flow of water has been diminished to the predetermined point, the counter weight will force the inner end of the member 25 downward disengaging the lug 39 from the lug 40 and the pressure of the water will close the clapper upon its seat shutting off any other flow.

The adjustment of the counter weight upon the stud 26 will determine the point at which

the water will shut off as will be readily understood.

By utilizing an air trapped tank and providing for the closing of the valve at a predetermined pressure flow of the water, not only the supply of water in the tank at the time the valve is open will be delivered to the bowl, but the additional water which will flow into the tank after the pressure in the latter falls below the pressure in the service pipe will also be delivered to the bowl, thus necessitating a much smaller tank than will otherwise be necessary; and as the water is delivered through the valve under pressure and therefore at high speed, its effectiveness in cleansing the bowl is increased, thus requiring a less quantity of water than where the ordinary gravity tanks are used.

The releasing of the handle 22 and the return of the dog to its normal position as shown in Fig. 3 prevents interference with the tilting of the member 25 and the backward movement of the tongue 37 during the closing of the clapper upon its seat.

Of course I do not wish to be limited to the exact details of construction as herein shown, as these may be varied within the limits of the appended claims without departing from the spirit of my invention.

Having thus fully described my invention, what I claim as new and useful is:—

1. A valve of the character described, comprising a casing, a supply pipe formed with the casing, said casing being at an angle to the supply pipe, an off-set also formed with said casing, a spindle journaled in the off-set, said spindle carrying a handle, a dog secured upon the spindle within the off-set, a tilting member, a shoulder carried by said member, a shoulder formed within the casing with which the first-mentioned shoulder is adapted to engage, said member being adapted to be slid in one direction by the action of the dog to bring said shoulder in engagement, a housing into which the tilting member telescopes, a bridge formed with the housing upon which the tilting member slides and tilts, a stationary pin projecting through slots formed in the housing, lugs carried by the tilting member, said lugs adapted to fit within seats and slots formed in the housing, a clapper carried by the tilting member, a seat formed within the casing upon which said clapper is adapted to be seated, and means for adjusting the downward tilting force of the inner end of the tilting member.

2. A valve of the character described, comprising a casing, a supply pipe formed with the casing, said casing being at an angle to the supply pipe, an off-set also formed with said angle, a spindle journaled in the off-set, said spindle carrying a handle, a dog secured upon the spindle within the off-set, a tilting member, a shoulder carried by said member, a shoulder formed within the casing with

which the first-mentioned shoulder is adapted to engage, said member being adapted to be slid in one direction by the action of the dog to bring said shoulders into engagement, 5 a housing into which the tilting member telescopes, a bridge formed on the housing upon which the tilting member slides and tilts, a stationary pin projecting through slots formed in the housing, lugs carried by the tilting member, said lugs adapted to fit within seats and slots formed in the housing, a clapper carried by the tilting member, and a seat formed within the casing upon which said clapper is adapted to be seated.

15 3. In a valve of the character described having a casing and a seat therein, a housing fitted to slide within said casing, means for holding said housing against rotation, said housing having seats and angular slots 20 formed therein and also having formed thereon a bridge, and a tilting member adapted to be tilted upon said bridge as a fulcrum, said member carrying the lugs for engagement with the seats and angular slots of the 25 housing and having openings in the lower portion thereof for the passage of water, and means for actuating said tilting member.

4. In a valve of the character described, a tilting member, said member having an angular face against which a clapper may be secured and also having cut-away portions in the under side thereof for the direction of the flow of water to the interior of said member, lugs carried by the member for attaching it to a housing, a tongue also carried by said member, a heel carried by the tongue, a dog for coacting with said heel to actuate the housing in one direction, a shoulder formed on the tongue and a shoulder located 35 in the casing for coacting with the first named shoulder to hold the clapper open during a given speed of the water flow through the 40 casing.

In testimony whereof, I have hereunto affixed my signature.

STEPHEN P. ENRIGHT.
